UNITED STATES PATENT OFFICE

172,262

COMBINED AUTOMOBILE LAMP LENS HOUSING AND GRILLE BAR

Richard F. Baird, Oak Park, Mich., assignor to
Chrysler Corporation, Highland Park, Mich., a
corporation of Delaware

Application June 24, 1953, Serial No. 25,630

Term of patent 7 years

(Cl. D14—18)

To all whom it may concern:

Be it known that I, Richard F. Baird, a citizen of the United States, residing in the city of Oak Park, county of Oakland, and State of Michigan, have invented a new, original, and ornamental Design for a Combined Automobile Lamp Lens Housing and Grille Bar, of which the following is a specification, reference being had to the accompanying drawings, forming part thereof, in which:

Fig. 1 is a front elevational view of a combined automobile lamp lens housing and grille bar showing my new design;

Fig. 2 is a top plan view thereof; and

Figs. 3, 4, 5, 6, 7, 8, 9 and 10 are sectional views

taken on the lines 3—3, 4—4, 5—5, 6—6, 7—7,
8—8, 9—9 and 10—10 respectively of Fig. 1.

I claim:

The ornamental design for a combined automobile lamp lens housing and grille bar, substantially as shown.
